United States Patent Office

Des. 189,133
Patented Nov. 1, 1960

189,133

KEY HOLDER

Bruce W. Anderson, 21 Crown Park Road,
Toronto, Ontario, Canada

Filed June 29, 1959, Ser. No. 56,579

Claims priority, application Canada Jan. 7, 1959

Term of patent 14 years

(Cl. D17—3)

The figure is a perspective view of a key holder showing my new design, the side opposite thereto being plain and unornamented.

I claim:

The ornamental design for a key holder, as shown and described.
